UNITED STATES PATENT OFFICE.

JAMES R. FLEMING, OF SCRANTON, PENNSYLVANIA.

MINING-CAR TRUCK.

Application filed March 30, 1922. Serial No. 548,014.

To all whom it may concern:

Be it known that I, JAMES R. FLEMING, a citizen of the United States, and a resident of Scranton, in the county of Lackawanna and State of Pennsylvania, have invented certain new and useful Improvements in Mining-Car Trucks, of which the following is a full, clear, and exact description.

This invention relates to car and truck mountings and in particular to mine cars wherein the body of the car is carried on a journal box in which the axle revolves.

A particular object of the invention is the provision of a construction that will allow of the body of the car being brought closer to the ground so that the miner will not have to lift his load so far each time in filling the car.

Another object is to provide a bearing plate, which, while being formed to allow of lowering the car body will also be prevented from slipping endwise.

Another object is the provision of means on the bearing member which will allow the journal box to be self-aligning.

Drawings.

Figure 1 is a sectional elevation taken through the journal box and car sill, showing the bearing plate and self-aligner and their position relative to the wheel and axle, a part of each of which only is shown.

Figure 2 is a section in elevation taken on the line 2—2 of Figure 1, and shows the method of fastening the journal box to the bearing plate.

Figure 3 is an end view of the outer end of the journal box with the wheel hub removed, a modified lubricating means being shown over that illustrated in Figures 1 and 2.

Figure 4 is a plan view of the journal box and its associated parts as illustrated in Figure 3, the car sill being omitted to show the bearing plate.

Description.

Referring to the drawings in detail, 10 denotes a car wheel mounted upon the usual axle 11, the latter of which passes through the journal box 12 which supports its apportioned weight of a mine car; the sill 13 of which has fixed therein the bearing plate 14 which contacts directly with the journal box 12.

55 In order that the car may be as low as

possible relatively to the ground, the sill 13 thereof is cut out semi-circularly as at 15 to receive the bearing plate 14 which is shaped at its center to conform with and fit snugly into said cut-out 15. The bearing plate is cast to comprise extensions 16 through which pass the bolts 17 through the medium of which the bearing plate is retained in position against the sill 13.

The bearing plate is also cast to comprise oppositely disposed crutches 18 located adjacent the edges of the semi-circular part thereof and into which extend the side flanges 25 formed on the journal box 12.

The journal box 12 comprises essentially 70 a cylindrical casting through which extends an axle receiving bore 19, and in which is formed an interior cylindrical recess 20 within which are disposed the roller bearings 21 between the journal box and which 75 is the cylindrical liner 22, the latter of which is used to prevent wear of the inner surface of the journal box by the bearings.

The end of the journal box is closed with a cover 23 which is affixed thereto in any 80 suitable manner and which is cast to provide packing glands 24 which act to retain the lubricant within the journal box.

The side flanges 25 are cast integral with the journal box and extend a distance equal 85 to the width of the bearing plate, terminating at their outer ends in lips 26 which are also cast integral with the journal box and bear against the outer edge of the bearing plate 14 at the points where the crutches 18 90 are formed therein.

It will be noted that the flanges 25 have up and down play in the crutches, and that the top portion of the journal box that underlies the bearing plate 14 is spaced therefrom by a central boss or knob 36, the top of which is rounded on a shorter radius than the semi-circular indentation in said bearing plate. This construction provides a self-aligning journal box and the weight of the 100 car is transmitted through said knob to the roller bearings 21.

The roller bearing recess 20 is provided in the lower portion thereof with a channel 27 disposed centrally thereof which constitutes 105 a lubricant holding chamber, into which lubricating oil is fed through the opening 28 which is normally closed by the screw plug 29.

The outer end of the journal box is formed 110 to provide an enlarged opening 30 which

2
receives the hub of the wheel 10, said opening being provided with an inset packing gland 31. Suitable wear washers 32 may be interposed between the inner face of the hub 5 and the journal box. An additional packing gland 33 is provided in the journal box between the opening 30 therein and the bearing recess 20 to prevent the lubricant from creeping out along the axle 11 to the wheel 10 hub.

In order to provide the filling of the lubricant chamber without going behind the wheels of the car as is required in using the opening 28, it will be noted upon reference to Figures 3 and 4 that the journal box is cast to provide an exterior boss 34 which extends from a point adjacent the outer end of said journal box to a point near the lubricant chamber, and which is bored as at 35, 15 said bore opening directly into the reservoir or chamber 27. With this arrangement the lubricant can be forced into the chamber from between the spokes of the wheel.

It can thus be seen that in this construction, the car is lowered appreciably more than in the case where a plain straight bearing plate is used. Also there is provided a self-aligning journal box which is essential in this type of car to maintain even wear 25 on the parts as the tracks of mines are usually crooked and present a rough path over which the cars must travel.

Claims.

1. A car of the class described, comprising a sill having a recess formed in the under side thereof, a bearing plate secured to the under side of said sill, and a journal box supported from said bearing plate, said bearing plate having a medially disposed depressed portion adapted to fit into said recess whereby the top of said journal box will be disposed above the face of the under side of said sill.

2. A car mounting of the character described, comprising a bearing plate, a journal box below said bearing plate, and means on said bearing plate for supporting said journal box centrally therefrom.

3. A car mounting of the character described comprising a car sill; a bearing plate fixed to said sill; a journal box dependently supported by said bearing plate; and cooperative means on said journal box and said bearing plate whereby said journal box is rendered self-aligning.

4. A car mounting of the class described,

comprising a sill, a bearing plate secured on the under side of said sill, a journal box disposed immediately below said bearing plate and in line with the transverse center thereof, means formed with said bearing plate for loosely supporting said journal box in position thereon, and means formed with said journal box and cooperative with said bearing plate whereby said journal box is rendered self-aligning.

5. A car mounting of the class described, comprising a sill having a semi-circular recess formed in the under side thereof, a bearing plate secured to the under side of said sill, a depressed portion formed on the transverse center of said bearing plate and snugly fitting into said recess, a journal box disposed immediately below said bearing plate and normally aligned with the depressed portion thereof, means formed on said bearing plate at opposite sides of said depressed portion for loosely supporting said journal box in position, and means formed at the top of said journal box and cooperative with the opposed face of the depressed portion of said bearing plate whereby said journal box is rendered self-aligning.

6. A car mounting of the class described, comprising a sill having a semi-circular recess formed in the under side thereof, a bearing plate secured to the under side of said sill, a depressed portion formed on the transverse center of said bearing plate and snugly fitting into said recess, a journal box disposed immediately below said bearing plate and normally aligned with the depressed portion thereof, crutches formed with said bearing plate at the opposite sides of said depressed portion, extensions formed at the opposite sides of said journal box and adapted for engagement with said crutches whereby said journal box is loosely supported in position, and a boss formed centrally of the top of said journal box and adapted to cooperate with the opposed face of the depressed portion of said bearing plate whereby said journal box is rendered self-aligning.

7. A car mounting of the character described, comprising a bearing plate, a journal box below said bearing plate, means on said bearing plate for supporting said journal box in position, and means on said bearing plate engaging said journal box at a central point thereon.

JAMES R. FLEMING.
